UNITED STATES PATENT OFFICE.

ALBERT O. BUCKIUS, JR., OF CHICAGO, ILLINOIS, ASSIGNOR TO THE NATIONAL MALLEABLE CASTINGS COMPANY, OF CLEVELAND, OHIO, A CORPORATION OF OHIO.

JOURNAL-BOX.

No. 882,487

Specification of Letters Patent. Patented March 17, 1903.

Application filed November 16, 1906. Serial No. 343,706.

To all whom it may concern:

Be it known that I, ALBERT O. BUCKIUS, Jr., of Chicago, Cook county, Illinois, have invented a new and useful Journal-Box, of which the following is a full, clear, and exact description, reference being had to the accompanying drawings, forming part of this specification, in which—

Figure 1 is a front elevation of a box showing the lid in a closed position. Fig. 2 is a similar view showing the lid opened. Fig. 3 is a side elevation; Fig. 4 is a partial vertical section on the line IV—IV of Fig. 1; Fig. 5 is a horizontal section on the line V—V of Fig. 1; and Fig. 6 is a partial top plan view.

The purpose of my invention is to provide a journal box for railway cars which will open edgewise, that is to say in the plane of the lid, and shall be without any of the disadvantages of instability and tendency to wear which heretofore have characterized the lids of such boxes.

In the drawings, 2 represents the journal box and 3 is the lid. This lid has lugs 4 which are pivotally connected by a bolt 5 to lugs 6, forming part of a rotary hinge-piece 7 connected by a pivot bolt 8 to a projection or lug 9 on the box. The spring 10 bears freely at one end upon the middle of the lid and at its other end is clamped by the head of the bolt 8 against the hinge-piece 7, the nut 11 by which the bolt is secured being on the inner side of the projection 9. The hinge-piece has a flat bearing upon the face of this projection and is designed to turn thereon without tipping. The tension of the spring 10 not only forces the lid against the seat on the box, but also presses the hinge-piece 7 firmly against its seat on the projection 9.

To open the lid the operator grasps the hand-piece 12 and pulls the lid outwardly, thus causing it to turn upon the axis of the bolt 5, and to draw away from its seat on the box. This outward motion of the lid is preferably limited in its extent by stops 13 on the lugs 4 which are adapted to engage corresponding stops 14 on the lugs 6. Having thus drawn the lid outward from its seat on the box, the operator lifts it edgewise on the axis of the bolt 8, thus moving it into the open position shown in Fig. 2, and this motion may, if desired, be limited by the stop 15 on the hinge piece which engages a stop 16 on the projection 9. During this edgewise mo-

tion of the lid the hinge-piece rotates, but it does not tip, for it is held closely to its seat by the spring 10, and therefore has no tendency to wear.

In closing the lid the operator moves it in the reverse direction on the axis of bolt 8, until it comes into closed position, at which time stops 17 on the inner side of the lid cease to bear on the edge of the box and the lid is forced inwardly against the box by the tension of the spring.

To prevent a too far downward motion of the lid in closing, I prefer to provide it with an edge flange 18 which engages the top of the box when the lid is closed. The stops 17 fit within the box when the lid is in a closed position and prevent the lid from being jarred open, for the lid must first be drawn outwardly on the axis of the bolt 5, before it can be moved into open position.

Within the scope of my invention the parts may be modified in various ways, and the pivot bolt 8 may if desired be applied to the top or the bottom of the box opening, instead of locating it at the side as shown in the drawing. The details of construction may also be modified in many ways, since

What I claim is:—

1. A journal-box, a hinge piece, and an edgewise movable lid pivotally connected to the hinge-piece, said hinge-piece being pivoted to turn in the direction of edgewise motion of the lid.

2. A journal-box, a hinge piece, an edgewise movable lid pivotally connected to the hinge-piece, said hinge-piece being pivoted to turn in the direction of edgewise motion of the lid, and a spring which bears upon the lid.

3. A journal-box, a hinge piece, an edgewise movable lid pivotally connected to the hinge-piece, said hinge-piece being pivoted to turn in the direction of edgewise motion of the lid, and a spring which bears upon the lid, said spring being attached to the hinge-piece.

4. A journal-box, a hinge piece, an edgewise movable lid pivotally connected to the hinge-piece, a pivot-bolt on which said hinge-piece is pivoted to turn in the direction of edgewise motion of the lid, and a spring which bears upon the lid, and is held by the pivot-bolt.

5. A journal-box, a hinge piece, an edgewise movable lid pivotally connected to the hinge-piece, said hinge-piece being pivoted

65

to turn in the direction of edgewise motion of the lid, and a stop by which the pivotal motion of the lid on the hinge-piece is limited.

6. A journal box, an edgewise movable lid pivoted to the box at one side, said lid fitting flat against the outer end of the box and having a flange at its upper edge to engage the top of the box when closed and also having a stop arranged to fit within the box; substantially as described.

7. A journal box, an edgewise movable lid having a flat bearing on the outer face of the box and provided with a stop on the inner face of the lid extending within the box when the lid is closed to prevent edgewise movement of the lid, and a flat spring arranged to bear against the outer face of the lid.

8. A journal box, an edgewise movable lid, and a rotary hinge-piece pivotally mounted on the box and having a close bearing against the same, said lid being hinged to the hinge-piece and a spring for the lid.

9. A journal box, an edgewise movable lid, and a rotary hinge-piece journaled on the box, said box having a stop by which the

motion of the hinge-piece on the box is limited.

10. An edgewise swinging journal box lid, and two hinges therefor, the axes of which are at right angles to one another, one of the hinges being a spring hinge.

11. The combination of a journal box, a main hinge on the box, a supplemental spring hinge upon the main hinge with its axis at substantially right angles to that of the main hinge, and a lid carried by the spring hinge.

12. The combination of a journal box, a main hinge on the box, a supplemental hinge upon the main hinge with its axis at substantially right angles to that of the main hinge, and a lid carried by the supplemental hinge, the main hinge being pivoted to turn in the direction of edgewise movement of the lid.

In testimony whereof, I have hereunto set my hand.

ALBERT O. BUCKIUS, JR.
